NONGLARE HEADLIGHT

Filed April 8, 1926

Inventor

Walter R. Greene

UNITED STATES PATENT OFFICE.

WALTER RAY GREENE, OF AMBRIDGE, PENNSYLVANIA.

NONGLARE HEADLIGHT.

Application filed April 8, 1926. Serial No. 100,641.

My invention relates to a non-glaring headlight for use upon motor vehicles, and aims to provide a novel and improved device of this character for efficiently directing the 5 rays of light therefrom down upon the roadway so as not to interfere with vehicles traveling in the opposite direction.

Another object of the invention is the provision of a drum shaped casing having an 10 electric bulb arranged therein adjacent the upper part of the cylindrical wall of said casing, the latter having a gradually reduced cylindrical portion at its forward end for restricting the size of the opening through 15 which the light rays may pass, the electric bulb being arranged above the horizontal plane of the uppermost part of the restricted opening for preventing the light rays from said bulb shining into the eyes of the driver 20 of an approaching automobile.

A still further object of the invention is to provide the casing with a reflector having the major portion thereof of substantially 25 cone shaped formation at the periphery of which there is a forwardly extending flange flared slightly outwardly as it extends forwardly and being slightly arcuate, said reflector being positioned with relation to the electric light bulb and forward part of the 30 casing so that all light rays reflected therefrom through the opening of the headlight will be in a downward direction.

It is also an object of the invention to provide a headlight of the kind indicated which 35 is simple in construction, can be manufactured at a small cost, and will be thoroughly efficient and practical in use.

With the foregoing and other objects in view, which will be apparent as the description 40 proceeds, the invention resides in the construction and arrangement of parts, as hereinafter described and claimed, it being understood that changes can be made within the scope of what is claimed without departing 45 from the spirit of the invention.

The invention is illustrated in the accompanying drawings, wherein:

Figure 1 is a longitudinal section through my improved headlight,

Figure 2 is a front elevation of the reflector, and

Figure 3 is a front elevation of the headlight.

In carrying out the invention, the numeral 55 10 designates a cylindrical casing having de-

tachably secured to the rear end thereof a slightly concaved end wall 11, and in the cylindrical casing against said rear wall is positioned a reflector 12, the detail construction of which will be set forth as the description proceeds. The forward end of the cylindrical casing 10 is tapered, as at 13, so as to be gradually reduced in size as it extends forwardly, to provide a restricted opening 14 at its forward end, and detachably mounted in said restricted opening is a lens 15 through which the light rays are projected, said lens being carried by a frame 16 which may be removed from the opening 14 with said lens.

Within the cylindrical casing 10 near the top of the concaved end wall 11 and secured in said end wall and reflector 12 is an electric light socket 17 into which an electric light bulb 18 is mounted, and extending from this 70 socket outside of the headlight are the usual wires 19 for supplying the current to the bulb. The bulb 18 is arranged above the horizontal plane of the uppermost portion of the restricted opening 14, so that any light rays 75 passing through said opening will necessarily be reflected from the reflector 12, which is of such shape or configuration that light rays reflected therefrom through the opening 14 will also be in a downward direction.

The reflector 12 has the major portion substantially cone shaped, as at 20, and at the periphery thereof is a forwardly extending annular flange 21 slightly arcuate or curved 80 as it extends forwardly. The curve of the cone shaped portion 20 is also very slight, extending practically straight from the periphery to the center, as clearly shown in Figure 1 of the drawings, and at its upper 85 end is provided with an opening 22 through which the lamp socket 17 extends, said socket being adapted to support the reflector in desired position, or at an angle with relation to the cylindrical casing 10, so that light rays 90 from the upper part of said cone shaped portion 20 will be reflected in a downward direction through the opening 14 as well as on to the lower portion of the tapered forward end 13 of the cylindrical casing 10. Light 95 rays reflected from the lower part of the cone shaped portion 20 of the reflector will be in a more horizontal plane than those reflected from the upper part thereof as illustrated by the dot and dash line in Figure 1 100 110

of the drawings. Light rays striking the forwardly extending peripheral flange 21 of the reflector will be reflected back into the cylindrical casing 10 and consequently aid in illuminating the interior of the headlight. The flange 21 extends at a greater angle from the cone-shaped portion 20 at the top and bottom thereof than at the sides, as illustrated in Figure 2 of the drawings, so that the forward edge of said flange will snugly engage and conform to the interior configuration of the cylindrical casing, as shown in Figure 1 of the drawings. It has been found that the light rays from the reflector projected through the opening 14 are very bright, and in order to dim the light the reflector may be colored or otherwise dulled in brightness at such points as indicated by the numeral 23 in Figure 2 of the drawings. However, it is to be understood that the device can be used without such coloring or dull surface if so desired.

At each side of the cylindrical casing 10 there is an apertured lug 25 through which extend the reduced ends of a yoke or U-shaped bracket 26 carried by an upright post 27 for supporting the same, said post 27 being secured to the vehicle in the usual manner.

In operation, the direct rays of light from the bulb 18 pass through the restricted opening 14 in a downward direction, and light rays from the reflector 12 are also directed downwardly due to the specific configuration of the reflector, and consequently all light

rays from the headlight are in a downward direction onto the road and not in the eyes of drivers operating vehicles traveling in an opposite direction.

Having thus described my invention, what I claim as new is:

1. A headlight of the character described comprising a casing having an opening in its forward end, a bulb positioned in said casing adjacent the top thereof, and a reflector positioned in said casing having a cone shaped portion and an annular forwardly extending flange arranged at the periphery of said cone shaped portion, said reflector being positioned at an angle in said casing so that the lower portion thereof extends forwardly with the flange in engagement with the interior of the casing irrespective of the fact that said reflector is arranged at an angle in the casing.

2. A headlight comprising a casing contracted at its forward end, a reflector mounted in the rear end of the casing and having a slightly conical body portion and an outwardly curved peripheral flange, said reflector being disposed within the casing with the upper portion of the conical body perpendicular and the lower portion inclined forwardly; together with an electric lamp projecting from said reflector near the upper end thereof.

In testimony whereof, I have affixed my signature.

WALTER RAY GREENE.
